(57) **CLAIM**

The ornamental design for an electrode array as shown and described.

DESCRIPTION

FIG. 1 is a perspective view of an electrode array in accordance with our design;

FIG. 2 is a top plan view of the electrode array of FIG. 1; FIG. 3 is a bottom plan view of the electrode array of FIG. 1;

FIG. 4 is a left side elevational view of the electrode array of FIG. 1;

FIG. 5 is a right side elevational view of the electrode array of FIG. 1;

FIG. 6 is a rear elevational view of the electrode array of FIG. 1; and,

FIG. 7 is a front elevational view of the electrode array of FIG. 1.

The broken lines having consistent dash lengths (dash-dash-dash) represent portions of the electrode array that form no part of the claimed design.

The broken lines having inconsistent dash lengths (short dash-medium dash-short dash) represent boundaries of the claimed design. As shown in FIGS. 1-3, the boundary lines are provided at an intersection between the body of the electrode array and a port for an electrical connection.
